United States Patent Office.

JOSEPH BELL ALEXANDER, OF WASHINGTON, DISTRICT OF COLUMBIA.

Letters Patent No. 97,854, dated December 14, 1869.

IMPROVEMENT IN LAMP-BURNERS.

The Schedule referred to in these Letters Patent and making part of the same.

To all whom it may concern:

Be it known that I, JOSEPH BELL ALEXANDER, of Washington, in the county of Washington, and District of Columbia, have invented a new and useful Improvement in Lamp-Burners; and I do hereby the following, when taken in connection with the accompanying drawings, and the letters of reference marked thereon, to be a full, clear, and exact description of the same, and which said drawings constitute part of this specification, and represent, in—

Figure 1, a side view of the entire burner, in perspective;

Figure 2, a vertical section of the entire burner;

Figure 3, a side view of the chimney-seat, body, or shell, and deflector, as struck up from one and the same piece of metal, in perspective;

Figure 4, a perspective view of a circular peripheral spring, as struck from one and the same piece of metal;

Figure 5, the perforated draught-plate, in perspective; and in

Figure 6, a side view, in perspective, of the wick-adjuster and wick-tube, with their casing, as when separated from the removable part of the burner.

Similar letters of reference denote like parts wherever they occur in the several figures, as follows:

A, the deflector.

B, the body or shell.

C, the chimney-seat.

D, the circular peripheral spring.

E, the corrugated and perforated draught-plate.

F, the cap enclosing the wick-tube and wick-adjuster.

G, the base, on which is cut the usual screw.

H, a circular throat, struck up in the centre of the draught-plate E, to admit of its slipping on and off the cap F.

I I, holes, to admit a current of cold air upon the inside of the base of the glass chimney.

K K, perforations in the draught-plate E, to supply cold air to the flame.

L L, projections, struck up on the inner circumference of the throat H, on the plate E.

M M, L-shaped indentures, struck in the sides of the cap F, to admit the projections L L, and constitute a bayonet-lock.

N N, comb-like teeth upon the periphery of the spring D.

O, a circular throat, struck downward in the centre of the spring D, which is made to slip tightly on the shell B.

P, the wick-tube.

R, the wick-adjuster.

S, the flame-slot.

This invention is an improvement upon an im-

proved lamp-burner, patented to me March 16, 1869, and numbered 87,898, and consists in the peculiar construction of the burner, and the arrangement for the support of the chimney.

To enable others to construct my improvement, I will proceed to describe the same, as illustrated in the accompanying drawings.

With a series of proper dies, I should strike up a circular blank, of sheet-metal, into a conical-shaped piece, as seen in fig. 3, and so form it as to constitute the deflector A, shell or body B, and chimney-seat C, from one and the same piece of metal.

Around the lower part of this I should perforate the holes I I, for the purpose of admitting a current of cold air upon the inside of the base of the chimney, to keep it cool, and also to supply invariably the exact amount of air to the flame above the deflector, as is necessary to perfect complete combustion.

The proper number and size of the holes I I is most important to the success of obtaining complete combustion, and a very bright white light, which, when once obtained in this burner, is unchangeable, as the great variations in the sizes of commercial chimneys make no increase or diminution in the volume of air supplied to the flame above the deflector.

The reverse of this is found in all burners with an elevated deflector, supported upon posts or standards, for with them it will be found that the air supplied to the flame above the deflector is deficient, or in excess, according to the variation in the size of the chimney, and the flame clouded, red, or smoky, as the consequence.

Having perforated the holes I I, I should then cut the flame-slot S.

I should then, with a proper blanking-die, punch out of sheet-metal, of proper thickness, a circular piece, having comb-like teeth upon its periphery, radiating from the centre, and a circle punched out of its centre for the purpose of forming the throat O.

I should then, with a proper die, strike this toothed metal ring, so as to form the downward throat or band O, and give the teeth N N the proper downward curve.

This forms the circular peripheral spring, as seen in fig. 4.

I should then, with a proper die, press the spring D, fig. 4, upon the piece A B C, fig. 3, and fasten it there by pointing, soldering, or swaging, as seen in fig. 1.

I should then, with a proper blanking and perforating-die, punch from sheet-metal, the circular piece, fig. 5, with its air-holes K K, and a circular piece punched from the centre, for the purpose of forming the throat or band H, which I should form with a

proper die, and with another suitable die force inward the projections L L.

Thus I should form the draught-plate E, fig. 5, which must be of the exact diameter to fit into a grooved edge, at the base of the piece, fig. 3, which grooved edge is turned over upon the edge of the draught-plate E, fig. 3, with a proper die, so as to swage the two pieces together, as seen in fig. 2.

This completes the upper or removable part of the burner.

I should then form the cap F, fig. 6, and with a suitable die, force into its opposite sides the L-shaped indentures M M, to correspond with and admit the projections L L, in the band H, of the draught-plate E, fig. 5.

I should then make the base G with its screw-thread, fig. 6, after the usual manner, and insert into it a wick-tube and wick-adjuster, in the ordinary way. I should then put on the cap F, so as to complete the form, seen in fig. 6, by swaging or soldering the parts together.

If this part, as seen in fig. 6, be now screwed into the collar of a lamp, the upper or removable portion may be slipped on or off at will, and locked firmly when on, by a slight twist, causing the projections L L to slip into the bayonet-lock indentures M M, as seen in figs. 1 and 2.

The chimney is attached by simply pushing it down over the teeth N N, of the spring D, in a direct manner, as no twisting is required.

This invention is a decided improvement upon the patent granted to me March 16, 1869, and has many superior advantages to render it useful and popular as a kerosene or light-oil burner.

I do not claim the use of a circular peripheral spring for supporting a chimney on a lamp-burner, when such spring is a part of or attached to a deflector elevated upon studs or posts, as in the patent of M. H. Collins, dated September 19, 1865, and others of the same nature.

What I do claim as new, and as my invention, and desire to secure by Letters Patent, is—

1. The spring D, with its curved teeth N N, and its throat C, substantially as described, and for the purpose set forth.

2. The L-shaped indentures M M, in the cap F, in combination with the projections L L on the inner circumference of the throat H, in the draught-plate E, substantially as described, and for the purpose set forth.

3. The combination of the spring D, with the piece A B C, comprising the deflector, shell or body, and chimney-seat, and with the draught-plate E, together with the wick-tube P, cap F, base G, and any of the wick-adjusters in use, when arranged together, substantially as described, and for the purpose set forth.

J. B. ALEXANDER.
